Primary Examiner — Mark A Goodwin(74) *Attorney, Agent, or Firm* — Lando & Anastasi, LLP(57) **CLAIM**

The ornamental design for a hydroponics growing machine, as shown and described.

DESCRIPTION

FIG. 1 is an upper perspective view of a hydroponics growing machine showing an embodiment of the design; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings illustrate portions of the hydroponics growing machine and form no part of the claimed design. The dash-dot-dash lines in FIGS. 1-5 and 7 do not form part of the claimed design and are used to illustrate a boundary of the claimed design.
